(57) **CLAIM**

We claim the ornamental design for an ant bait station, as shown and described.

DESCRIPTION

FIG. 1 is a perspective view of an ant bait station, showing a first embodiment of our new design in an open position;

FIG. 2 is a perspective view of FIG. 1 in a closed position;

FIG. 3 is a right-side elevational view of FIG. 2;

FIG. 4 is a front elevational view of FIG. 2;

FIG. 5 is a rear elevational view of FIG. 2;

FIG. 6 is a front elevational view of FIG. 2;

FIG. 7 is a top plan view of FIG. 2;

FIG. 8 is a bottom plan view of FIG. 2;

FIG. 9 is a perspective view of a second embodiment thereof in the open position;

FIG. 10 is a perspective view of the second embodiment in the closed position;

FIG. 11 is a right-side elevational view of FIG. 10;

FIG. 12 is a left-side elevational view of FIG. 10;

FIG. 13 is a rear elevational view of FIG. 10;

FIG. 14 is a front elevational view of FIG. 10;

FIG. 15 is a top plan view of FIG. 10; and,

FIG. 16 is a bottom plan view of FIG. 10.
